ELLIOTT FISHER COMPANY, OF NEW YORK, N. Y., A CORPORATION OF DELAWARE

TYPEWRITING MACHINE

Application filed September 15, 1927. Serial No. 219,607.

This invention relates to power-driven typewriting mechanisms, and more specifically to that class of machines where electromagnetic forces are employed to drive the type-bars to the typing position following a 5 partial depression of the associated character-keys.

In the prior art of electromagnetic type-bar-driving mechanisms, individual solenoids 10 were employed to directly actuate the key-mechanisms or a universal actuating member for all of the key-mechanisms was provided to be actuated by one or more solenoids. Such mechanisms were objectionable because 15 they were too slow to respond to speedy operation, and, furthermore, special provisions were required to prevent arcing at the contact points.

Another form in practice included a key- 20 actuated toothed pendant shiftable by the initial depression of a key-lever into engagement with a rotating toothed drum. As long as the tooth of the pinion and the teeth of the drum remain sharp, this method 25 proved effective, but just as soon as the teeth showed the effect of wear by becoming blunt at the points, the pendant would skitter over the teeth of the drum and gradually require a greater pressure at the key-cap to effect 30 an operative interlock of the teeth.

It is a purpose in the present invention to employ a constantly rotating magnetized cylinder that is effective to actuate any type-bar without any form of electrical make and 35 break in the circuit except the starting switch in the main line circuit which is operated to start the motor and magnetize the cylinder. The cylinder may include armored built-up coils, each coil wound so as to reverse the magnetic polarity of adjoining coils, and when the coils are assembled end to end 40 as a series, they become a magnetic unit having the magnetism uniformly distributed throughout its length.

45 It is further proposed to provide each key-lever with a pendant-armature pivotally mounted on the key and normally spring held out of the magnetic field of the cylinder and having mechanical means operative, by an 50 extremely short initial dip of the key, to

force the pendant within the magnetic field of the cylinder, and through the magnetic attraction of the armature to the rotating cylinder to establish a clutching engagement between the armature and cylinder. The 55 friction obtained by magnetic attraction will draw the pendant downwardly as the cylinder rotates and with it the associated key-lever, to throw its type-bar to the typing position. Each pendant is provided with a 60 wedging element of non-magnetic metal and the pendant is adjustably timed to the swing of the type-bar, to become effective just in advance of the typing moment to cam the armature out of the magnetic field of the cylinder and thus establish a free return movement for the armature, the key-lever and the 65 type-bar.

Another feature provides for a predetermined loss of motion between the key-levers 70 and the associated type-bar-actuating mechanism, so that each key may be initially depressed to vibrate its pendant-armature into the field of the magnetized cylinder without raising the associated type-bar from the type-rest, and thus throwing the burden of typing 75 wholly upon the power-driven connections.

The recoil of a type-bar after its impact against the platen is more rapid than the restoration of the spring-restored key-lever 80 and connections; hence, any positively connected type-bar is retarded on its return stroke by the slower restoring key-lever and connections. By the employment of a lost or idle motion between the key-lever and type-bar driving bell-crank to enable the key to vibrate its armature into the field of the magnetized cylinder, and by timing the camming 85 of the armature out of the magnetic field of the cylinder prior to the typing operation, the type-bar is provided with a free movement to type under its own momentum and recoil under its own power independently of the power-driving mechanism. Hence, the sharp impact and the unimpeded recoil of the 90 type-bar promotes both sharp and clean-cut typing upon the work-sheet and speeds up 95 the typing elements.

This application discloses improvements 100 upon the mechanism disclosed in the applica-

tion of Alfred E. Oswald, Serial No. 122,537, filed July 15, 1926. Said Oswald application embodies claims that broadly cover the present application.

5 Other features and advantages will hereinafter appear.

In the accompanying drawings,

10 Figure 1 is a central, vertical section through an Underwood standard typewriting machine, showing only such parts of the typewriting mechanism necessary to co-operate with the power-driven mechanisms forming the subject-matter of this invention.

15 Figure 2 is an enlarged view, in perspective, of the extreme left-hand key of the keyboard and its connecting and operating parts that co-operate with the power-driven magnetized cylinder.

20 Figure 3 is a partial front elevation, in vertical sections, the sectional plane of the left-hand half of the figure being taken between the two upper banks of keys, and the plane of the right-hand half of the figure being taken just in front of the cylinder.

25 Figure 4 is an enlarged longitudinal section through the magnetic cylinder, showing the arrangement of the coiled sections and the manner of wiring the two end sections of the cylinder to the regular commutators.

30 Figure 5 is a diagrammatic view, showing the key-lever drawn down to a position where the armature has been cammed out of the magnetic field of the cylinder and is about to respond to the tension of the armature-spring to further widen the air-gap between the armature and the cylinder for the idle return of the armature with the type-bar at the end of its driven stroke just in advance of the typing position at the platen.

40 Figure 6 is a diagram of the circuits that include the motor-starting switch and the rheostat in the cylinder circuit to regulate the degree of magnetism of the power-driven type-bar-actuating cylinder.

45 Numeral and alphabet keys 10 and 11 operate key-levers 13 fulcrumed at their rear ends upon a rod 14 and spring-pressed to their normal positions by individual springs 15. Each key-lever 13 is provided with a

50 stud 16 engageable within a slot 17 formed within one arm of a bell-crank-lever 18 pivotally supported upon a fulcrum-wire 19, with the other arm having a pivotal connection 20 to a type-bar 21 fulcrumed upon a segment-wire 22 and operative to guide the type-bar upwardly and rearwardly against a platen 23 at each depression of the key. The platen 23 is rotatably mounted in a carriage 24 arranged to travel upon carriage-rails 25

60 and 26 under the influence of a spring-motor 27 connected by a tape 28 to the carriage and controlled by carriage-feeding mechanism 29 operated through the engagement of each type-bar 21 with a curved universal bar 30 in the well-known Underwood manner.

For the purpose of the present invention, each key-lever 13 may have an extension 31 to provide a support for an adjustable yoke or U-shaped saddle 32 to straddle the extension, pivotally held thereupon by a pivot-pin 33 and adjustable relatively to the extension by two set screws 34 threaded through the wall of the yoke to bear against the edge of the extension and operate to tilt the free end of the yoke up and down for purposes to appear. 70 The free ends of each yoke 32 carry a pivot-pin 35 upon which is suspended a soft permeable metal pendant-armature 36 formed with a section 37 bent over at right angles to provide a wide flat face 38. The lower ends of the armatures 36 may be held in vertical alignment by a suitable comb 39 secured at each end to the side walls of the machine-frame, as by screws 40. The slots of the comb also provide stop-faces against which the 80 armatures are normally held under the tension of individual springs 41 flexed between the armatures and ears 42 forming a part of each key-lever-extension 31. It will be noted at this point that the pivotal point 35, when 90 depressed by the key-levers will have a substantially straight up-and-down movement, and an operative pull of the armatures to depress the key-levers will be in a straight line. 95

To co-operate with the armatures 36, a cylinder 43 is assembled upon a shaft 44 to rotate therewith and present a longitudinal peripheral face parallel to the series of armatures. The shaft may have bearings in the free ends of two arms 45 and 46, one arm at each end of the cylinder and permanently secured to a rock-shaft 47 having end bearings in the side walls of the machine-frame, said shaft and arms forming an adjustable carrier for the cylinder. One arm, as 46, may have a short arm 48 disposed between two adjusting screws 49, carried by a lug 50, forming a part of the side wall of the frame. The adjustment of the screws 49 shifts the arm 48 to rock the shaft 47 and raise or lower the cylinder 43 to adjust its position relatively to the series of armatures 36. The shaft 44 may project beyond one side wall of the frame where the free end may be provided with a worm-gear 51 driven by a worm 52 secured to the driving shaft of a motor 53. Means are provided so that the vertical adjustment of the cylinder does not interfere with the motor-drive. The power-driven cylinder rotates in the direction of the arrow, Figure 1, or in a direction to exert a peripheral downward pull upon the armatures 36 when one of the latter is in surface contact with the rotating face of the cylinder. 110 115 120

The detail construction of the cylinder 43 is shown at Figure 4, where a plurality of permeable iron sections 54 are assembled upon the shaft 44 to form enclosed compartments 55, each compartment to house a magnetic coil. Each section 54 is formed with a web 125 130

56 arranged to slide along the shaft for purposes of assembly, and formed with a tongue 57 that enters a longitudinal groove 58 in said shaft to provide for driving connections between the sections and the shaft 44.

The cylindrical edges of adjoining sections may be separated by brass rings 59, and the whole series of sections and rings are assembled and maintained in co-operative relation upon the shaft 44 by collars 60 secured to the shaft, and disposed to bear against the webs of the two outer sections and hold the assembled sections together as a cylindrical unit.

It will be noted at Figure 4 that the assembly of two adjoining sections 54 upon the shaft provides a chamber formed between the two webs, and within the chamber a previously-wound helix or solenoid may be assembled that becomes operative when excited by an electric current to supply magnetic energy to the two webs and the peripheral walls of the adjacent sections of opposite polarity; that the winding of the helix 61 in one direction may convey a south polarity to the web 56^a and cylindrical section 54^a, while a north polarity may be conveyed to the web 56^b and the cylindrical section 54^b; that as unlike magnetic poles neutralize each other, it is clear that only similar poles can occupy adjoining spaces, and magnetically co-operate to increase the number of magnetic lines of force and a proportional density of magnetism or magnetic density, and, hence, by changing the direction of winding, the helix 62 will convey a north polarity to the web 56^b and the cylindrical section 54^b, while a south polarity is conveyed to the next successive section 54, not shown; that each web and section 54, except the two outer end sections, are magnetized by two adjoining helixes that co-operate to produce magnetism of similar polarity and of double density; and that the ring-filled air or flux gap 59 will break up the flow of magnetic waves of opposite polarity and further present an unbroken cylindrical surface to the armatures 36.

In the assembly of the cylinder 43, the first section 54^a may be forced along the shaft 44 to abut the collar 60. The previously-wound-up helix 61 may be inserted within the section against the web 56^a, one terminal wire 63 passing through the web 56^a to the outside of the cylinder. The second section 54^b may now be forced into position along the shaft to enclose the coil 61 with the opposite terminal 64 passing through the web 56^b where it is joined as by soldering at 64^a to the terminal of the second coil or helix 62. In this manner the cylinder is built up of successive coils and sections, and held in assembled relation by the two collars 60, the successive coils representing a continuous circuit with terminal wires passing out of the cylinder-heads.

To provide a continuous flow of current through the coils of the cylinder, each terminal-wire 63 and 64 may be connected to a commutator ring 65 secured to and insulated from each collar 60. To convey current to the two rings, brushes 66 may be secured to insulated supports 67 as by a screw 68, the brushes having a permanent contact with the rings that rotate with the cylinder.

The diagram for the current from the supply or lead wires is shown in Figure 6, where the motor-circuit is provided with a starting switch 69 and a branch current is established to shunt the current to the two brushes 66 through a suitable variable resistance 70 in the brush-circuit. The closing of the switch 69 starts the motor to rotate the cylinder 43 and jointly conveys current to the coils within the cylinder that develop a permanent magnetic field for the rotating cylinder as long as the motor is operative to drive the cylinder.

The description up to this point includes a power-driven built-up cylinder 43 having a rotary magnetic field to co-operate with armatures 36 hanging pendent from key-levers 13 just beyond the magnetic pull of the electrically-excited cylinder. To shift these armatures to a position where the magnetic attraction of the cylinder will draw the armatures into clutching engagement therewith, by an initial depression of the key and without conveying movement to the inert type-bar, the lower or free end of each armature may be provided with a stud 71 to overlie a cam-face 72 formed by bending the free end of a tripping arm 73 over at right angles. Each arm 73 may be mounted upon a horizontally disposed tie-rod 74 permanently secured at each end to supporting plates 75 secured to each side wall of the machine-frame by screws 76. Each arm 73 may have a hub 77 to provide a suitable bearing for the arm upon the rod 74 and also serve as spacers to maintain a proper alignment of the arm to the armatures 36. A stop-bar 78 may be secured at each end thereof by screws 79 threaded into lugs 80 carried by each plate 75 and adjusted to contact against the series of arms 73, each arm being normally pressed against said bar by individual springs 81.

The depression of any key, as 10, to the dotted position of 10^a in Figure 1 lowers the armature 36 to bring the stud 71 into contact with the cam-face 72 of its associated arm 73, and the lower end of the armature is forced towards the face of the magnetized cylinder 43 and against the tension of its spring 41. The relation of the parts is such that, when the key is depressed to the dotted position of 10^a, the stud 71 will ride off the cam-face 72 and the armature 36 will be mechanically forced against the face of the cylinder 43, and the stud 16 of the key-lever 13 will move to abut the lower edge of the slot 17 but without actuating the bell-crank 18 to lift the type-bar, and from this position the further

depression of the key-lever will actuate the bell-crank to throw the type-bar to the typing position. This would be the normal operation of the typing system when the cylinder is inactive and non-magnetic.

5 When the cylinder is energized or saturated with magnetism from a continuous flow of current, it is obvious that the initial depression of a key will cam its armature towards the cylinder to a point where the magnetic attraction will supersede the key-control of the armature, and the armature will be drawn into magnetic clutching contact with the face of the cylinder before the key 10 has actually reached the depressed 10^a position. Or, in other words, the key only starts the swing of the armature and the magnetism of the cylinder finishes the swinging movement of the armature into clutching engagement with the cylinder.

15 As the cylinder is continuously rotated and the magnetic saturation of the cylinder is a constant factor, it is proposed to mechanically and automatically sever the magnetic effect of the cylinder upon the armatures, at a uniform position predetermined by a position for the type-bars just in advance of the typing position as shown in Figure 5. The downstroke of the key-levers 13, whether depressed manually or by the power-driving mechanism, is arrested by a stop-bar 13^a secured to the machine-frame and common to all the key-levers, but may not be used.

20 The momentum of the key-lever and its connected parts is employed to effect a separation of the depressed armature from the magnetic field of the cylinder. Each armature 36, besides being provided with a section 37 that is responsive to the magnetism of the cylinder, is also provided with a section 30 that is non-responsive to magnetic attraction and mechanically effective to release the armature from the magnetic control of the cylinder. To this end, each armature 36 is 25 provided with a non-magnetic section 82 secured to the armature in any suitable manner, said section 82 having a beveled face 33 positioned as a continuation of the permeable face 38 and operative to not only cam the armature away from the cylinder, but to cut or sever the magnetic forces of the cylinder from the armature by interposing itself between them.

30 This result is shown at Figure 5, where the armature 36 has been wedged away from the cylinder by the section 82 and the armature is about to respond to the tension of the spring 41 to further swing the armature outside the magnetic field of the cylinder until arrested by a stop 84. In this position, the stud 71 on the armature swings under the vertical plane of the cam-face 72, and, when the spring 15 restores the key-lever 13, the armature 36 will be lifted until its stud 71 engages under 35 the cam-face 72, forcing the arm 73 to vibrate

against the tension of the spring 81 until the passage of the stud permits the restoration of the arm 73 under the stud 71 as at the normal ineffective position of the armature.

It will be further noted at Figure 5 that the down-stroke of the key is arrested by the bar 13^a but the thrown type-bar is short of the typing position. The type-bar is shown positioned at a point of its greatest velocity, and its momentum will carry the bar against the usual anvil 23^a to type with a staccato blow, so essential to sharp, clean typing, and the recoil of the type-bar back to its position in Figure 5 will be unimpeded by connections to the slower returning key-lever, because of the looseness of the stud 16 within the slot 17.

From the above description, it will be seen that the operation of the power-driven mechanism is free of any form of make-and-break control of an operating electric current; that the co-operation of the surface of the magnetized cylinder with the flat faces of the armatures will last indefinitely without showing any effect from wear; that the machine 90 may be manually manipulated to actuate the type-bars in the usual manner at will; that the power-driven organization can be applied to existing machines without radical changes in the standard parts; that the initial depression of a key renders the power-driven mechanism operative before the type-bar is lifted from a type-rest; that at the actual typing moment the type-bar is free of the retarding effect of a slow restoring key-lever and connections; that, contrary to conventional methods of type-bar actuation, the key-levers have a free initial dip and the type-bar has a free final movement to type; that the magnetic cylinder may be adjusted to raise or lower 95 its horizontal magnetic axis relative to the armatures; that each armature may be individually adjusted up or down to time the passage of the non-magnetic wedging interponent in cutting through the lines of force 100 of the cylinder at approximately a uniform point common to the whole series of armatures; that the velocity of the type-impact is proportional to the velocity of the rotating cylinder, and that this velocity may be varied 105 at will in a well-known manner of motor-control; that the magnetic lines of force derived from the coils of the cylinder may be made variable up to the point of saturation to the 110 least amount of magnetic density necessary to frictionally bind the armatures to the cylinder during the pulling movement of the armatures to depress a key-lever to type; and that, while the driving mechanism is shown and described to actuate the key-levers of the typing system of a typewriting machine, 115 it is obvious that the novel manner of actuating a key-lever through a rotatable magnetic friction-clutch can also be applied to other forms of machines where depressible

120

125

130

keys are employed to selectively actuate a mechanism.

While the cylinder 43 is shown and described as being driven by an electric motor, it will be seen that said motor may be cut out of the electric circuit and the cylinder rotated independently by any other convenient source of power; and that, wherever the term "permanently magnetized" is employed herein in connection with the cylinder 43, it will be understood to refer to the operative magnetic state of the cylinder during a typing period or during the full period the cylinder driving motor is active.

It will also be understood that the magnetized cylinder becomes a rotary friction clutching member; that the armatures pendent from each key-lever constitute individual friction clutching elements co-operative with the cylinder through magnetic attraction, to convert the rotary motion of the cylinder into a reciprocation for any key-vibrated armature to drive a key-lever to type; that the intermediaries 36 can be individually adjusted to the key-levers by the manipulation of the two screws 34, to determine the initial position for each intermediary and time the release thereof into the magnetic clutching field of the cylinder; that the cylinder 43, as a whole, may be adjusted relatively to the intermediaries 36 by the screws 49; and that each section 54 of the magnetic cylinder has polarities the same as the polarity of the adjusted sections, and the series of sections become effective to establish a universal magnetic field that is substantially uniform throughout the length of the cylinder.

Variations may be resorted to within the scope of the invention, and portions of the improvements may be used without others.

Having thus described my invention, I claim:

1. In a key-actuated machine, the combination with a depressible key-lever operative to control a mechanism, of means brought into co-operation by the partial depression of said key-lever to complete the depression thereof, said means including a continuously rotating permanently magnetized actuator and an armature attached to and movable by said key-lever into the magnetic field of said actuator to establish a magnetic clutch-connection between the rotating actuator and the key-lever.

2. In a key-actuated machine, the combination with a depressible key-lever operative to control a mechanism, of means brought into co-operation by the partial depression of said key-lever to complete the depression thereof, said means including a continuously rotating permanently magnetized actuator and an armature attached to and movable by said key-lever into the magnetic field of said actuator to establish a magnetic clutch-connection between the rotating actuator and the

key-lever, and means brought into the magnetic field of the actuator by the movement of the actuator-driven armature that becomes operative to free the armature from the magnetic clutch of the actuator at the end of a full depression of the key.

3. In a key-actuated machine, the combination with a depressible key-lever operative to control a mechanism, of means brought into co-operation by the partial depression of said key-lever to complete the depression thereof, said means including a continuously rotating permanently magnetized actuator and an armature attached to and movable by said key-lever into the magnetic field of said actuator to establish a magnetic clutch-connection between the rotating actuator and the key-lever, and non-magnetic means brought into the magnetic field of the actuator by the movement of the actuator-driven armature that becomes operative by cutting the magnetic lines of force of the actuator to free the armature from the magnetic clutch of the actuator at the end of a full depression of the key.

4. In a key-actuated machine, the combination with a depressible key-lever operative to control a mechanism, of means brought into co-operation by the partial depression of said key-lever to complete the depression thereof, said means including a continuously rotating permanently magnetized actuator and an armature attached to and movable by said key-lever into the magnetic field of said actuator to establish a magnetic clutch-connection between the rotating actuator and the key-lever, and non-magnetic camming means brought into the magnetic field of the actuator by the movement of the actuator-driven armature that becomes operative by cutting the lines of force of said actuator and camming the armature free from the magnetic clutch of the actuator at the end of a key-stroke to release the key-lever.

5. In a key-operated machine having key-levers, a power-driven means for automatically completing the depression of partially depressed key-levers to fully actuate a mechanism, said driven means including a positively rotating electro-magnetized unit, a normally inoperative magnetically attracted armature secured to each key-lever, and means co-operative with each armature upon the partial depression of its key-lever to vibrate the armature into the power-driven magnetic clutching field of the actuator to complete the depression of the key-lever and actuate the mechanism.

6. In a typewriting machine having type-bars connectible to depressible key-levers, a power-driven continuously rotating permanently magnetized key-lever actuator, and means carried by each key-lever and movable by the initial depression of said key-lever into the magnetic field of the rotating actu-

ator to become effective to complete the depression of the key-lever and actuate its type-bar.

7. In a typewriting machine having type-bars connectible to depressible key-levers, a power-driven continuously rotating permanently magnetized key-lever actuator, and an armature carried by each key-lever and movable by the initial depression of said key-lever into the rotary magnetic field of the actuator to become effective to complete the depression of the key-lever and actuate its type-bar.

8. In a typewriting machine having type-bars connectible to depressible key-levers, a power-driven continuously rotating permanently magnetized key-lever actuator, an armature carried by each key-lever and movable by the initial depression of said key-lever into the magnetic field of the rotating actuator to become effective to complete the depression of the key-lever and actuate its type-bar, and camming means operative to withdraw the armature from the rotating field of the magnetized actuator when the key-lever is fully depressed.

9. In a typewriting machine having type-bars connectible to depressible key-levers, a power-driven continuously rotating permanently magnetized key-lever actuator, an armature carried by each key-lever and movable by the initial depression of said key-lever into the magnetic field of the rotating actuator to become effective to complete the depression of the key-lever and actuate its type-bar, and camming means operative to force the armature out of the field of the magnetized actuator, said means including a non-magnetic section secured to the armature.

10. In a typewriting machine, the combination with a type-bar having a depressible key-lever, of a motor-driven permanently magnetized actuator for the key-lever, and means brought into operative engagement with said actuator by the initial depression of the key-lever to render said actuator effective by its magnetism to complete the depression of the key-lever to actuate the type-bar.

11. In a typewriting machine, the combination with a system of type-actions including type-bars, of a power-rotated cylindrical magnet, an individual armature connected to each of said type-actions, and means to present the armatures selectively to said magnet to be drawn thereagainst whereby the revolving magnet frictionally drives the selected armature and type-action, means being provided for disconnecting the armature from the magnet when the type-bar has been driven, permitting the return of the type-action and armature to normal positions independently of the magnet.

12. In a typewriting machine, the combination with a system of type-actions including type-bars, of a power-rotated cylindrical magnet, an individual armature connected to

each of said type-actions, means to present the armatures selectively to said magnet to be drawn thereagainst whereby the revolving magnet frictionally drives the selected armature and type-actions, means being provided for disconnecting the armature from the magnet when the type-bar has been driven, permitting the return of the type-action and armature to normal positions independently of the magnet, said disconnecting means including a device called into action by the driving force of the magnet upon the individual armature, for disengaging the latter from the magnet, and springs for returning the type-actions to normal positions.

13. In a typewriting machine, the combination with a system of type-actions including type-bars, of a power-rotated cylindrical magnet, an individual armature connected to each of said type-actions, means to present the armatures selectively to said magnet to be drawn thereagainst whereby the revolving magnet frictionally drives the selected armature and type-actions, means being provided for disconnecting the armature from the magnet when the type-bar has been driven, permitting the return of the type-action and armature to normal positions independently of the magnet, said disconnecting means including a device called into action by the driving force of the magnet upon the individual armature, for disengaging the latter from the magnet, and springs for returning the type-actions to normal positions, said disconnection between the armature and the magnet being effected before the type prints, and the printing stroke of the type being completed by momentum.

14. In a typewriting machine, the combination with a system of type-actions including type-bars, of a power-rotated cylindrical magnet, an individual armature connected to each of said type-actions, means to present the armatures selectively to said magnet to be drawn thereagainst whereby the revolving magnet frictionally drives the selected armature and type-action, means being provided for disconnecting the armature from the magnet when the type-bar has been driven, permitting the return of the type-action and armature to normal positions independently of the magnet, said disconnecting means including a device called into action by the driving force of the magnet upon the individual armature, for disengaging the latter from the magnet, and springs for returning the type-actions to normal positions, said disconnection between the armature and the magnet being effected before the type prints, and the printing stroke of the type being completed by momentum, said type-actions including levers and means to arrest each lever at the conclusion of its down stroke, a loose connection being provided between said lever and the type, permitting the completion of the

- printing stroke of the type after the arrest of said lever.
15. In a typewriting machine, the combination with a type-bar having a compressible key-lever, of a motor-rotated magnetized mechanism to drive the key-lever, and means intermediate the key-lever and the type-bar enabling the key-lever to be operatively connected to said magnetized driven mechanism before motion is conveyed to the type-bar by said key-lever, so that the type-bar will be actuated wholly by the power-driven key-lever.
16. In a typewriting machine, the combination with a type-bar having a compressible key-lever, of a motor-rotated magnetized mechanism to drive the key-lever, and connections intermediate the key-lever and the type-bar enabling the key-lever to be operatively connected to said magnetized driven mechanism before motion is conveyed to the type-bar by said key-lever, so that the type-bar will be driven to type wholly by the power-driven key-lever, said intermediate means including a pin on the key-lever having a loose driving connection to the type-bar.
17. In a typewriting machine having type-bars connectible to compressible key-levers, a continuously rotating actuator common to all the key-levers, said actuator having a permanent magnetic field, and an intermediary carried by each key-lever operative, upon entering the magnetic field of the actuator by the initial depression of a key-lever, to establish a magnetic clutching engagement with said actuator to complete the depression of the key-lever and actuate its type-bar.
18. In a typewriting machine having type-bars connectible to compressible key-levers, a continuously rotating actuator common to all the key-levers, said actuator having a permanent magnetic field, and an intermediary carried by each key-lever operative, upon entering the magnetic field of the actuator by the initial depression of a key-lever, to establish a magnetic clutching engagement with said actuator to complete the depression of the key-lever and actuate its type-bar, each intermediary having a non-magnetic cam-face operative to wedge itself between the rotating actuator and intermediary to force the latter out of the magnetic field of the actuator at the end of a full depression of the key-lever.
19. In a typewriting machine having type-bars connectible to compressible key-levers, a continuously rotating magnetic actuator common to all the key-levers, said actuator including a magnet-coil operative to establish a permanent magnetic field on the periphery of the actuator, and a normally inoperative armature carried by each key-lever and swingable by the initial depression of the key-lever into the magnetic field of the actuator to complete the depression of the key-lever and actuate its type-bar.
20. In a typewriting machine having type-bars connectible to compressible key-levers, a continuously rotating magnetic actuator common to all the key-levers, said actuator including a magnet-coil operative to establish a permanent magnetic field on the periphery of the actuator, and a normally inoperative armature carried by each key-lever and swingable by the initial depression of the key-lever into the magnetic field of the actuator to complete the depression of the key-lever and actuate its type-bar.
21. In a typewriting machine, a series of key-levers to actuate type-carriers, an electromagnetic actuator for the key-levers, a power-means for continuously rotating the magnetic actuator, a coupler carried by each key-lever, and means operative during the initial depression of each key-lever to vibrate the coupler into the magnetic field of the key-lever actuator to complete the depression of the semi-depressed key-lever to type.
22. In a typewriting machine, a series of key-levers to actuate type-carriers, an electromagnetic actuator for the key-levers, a power-means for continuously rotating the magnetic actuator, a coupler carried by each key-lever, means operative during the initial depression of each key-lever to vibrate the coupler into the magnetic field of the key-lever actuator to complete the depression of the semi-depressed key-lever to type, and other means operative to vibrate the coupler out of the magnetic field of the actuator upon the full depression of the key-lever by said actuator.
23. In a typewriting machine, a series of key-levers to actuate type-carriers, an electromagnetic actuator for the key-levers, a power-means for continuously rotating the magnetic actuator, a coupler carried by each key-lever, camming means operative during the initial depression of each key-lever to vibrate the coupler into the magnetic field of the key-lever actuator to complete the depression of the semi-depressed key-lever to type, and other camming means operative to vibrate the coupler out of the magnetic field of the actuator upon the full depression of the key-lever by said actuator.
24. In a typewriting machine having type-bars and key-levers to actuate the type-bars, a normally inoperative coupler for each key-lever, a power-driven constantly rotating permanently magnetized actuator common to all the couplers, and means operative to shift each coupler into the magnetic field of said actuator for a key-lever-driving connection with the actuator by a manual initial depression of its key-lever.
25. In a typewriting machine having type-

- bars and key-levers to actuate the type-bars, a normally inoperative coupler for each key-lever, a power-driven permanently magnetized actuator common to all the couplers, and a cam for each coupler operative to shift the coupler into the magnetic field of said actuator for a key-lever-driving connection with the actuator by a manual initial depression of its key-lever.
26. In a typewriting machine having type-bars and key-levers to actuate the type-bars, a normally inoperative coupler for each key-lever, a power-driven permanently magnetized actuator common to all the couplers, a cam for each coupler operative to shift the coupler into the magnetic field of said actuator for a key-lever-driving connection with the actuator by a manual initial depression of its key-lever, and means carried by each coupler which in entering the magnetic field of the actuator operates to remove said coupler from the magnetic clutch of said actuator to release the key-lever at the end of a full depression in typing.
27. In a typewriting machine having type-bars and key-levers to actuate the type-bars, a normally inoperative coupler for each key-lever, a power-driven permanently magnetized actuator common to all the couplers, a cam for each coupler operative to shift the coupler into the magnetic field of said actuator for a key-lever-driving connection with the actuator by a manual initial depression of its key lever, and camming means carried by each coupler which, in entering the magnetic field of said actuator, operates to cam said coupler out of the magnetic field of the actuator and release the fully depressed key-lever.
28. In a typewriting machine having type-bars and key-levers to actuate the type-bars, a normally inoperative coupler for each key-lever, a power-driven permanently magnetized actuator common to all the couplers, a cam for each coupler operative to shift the coupler into the magnetic field of said actuator for a key-lever-driving connection with the actuator by a manual initial depression of its key-lever, and camming means having non-magnetic properties carried by each coupler which, in entering the magnetic field of said actuator, operates to cam said coupler out of the magnetic field of the actuator and to release the coupler and key-lever from the power-driven actuator at the end of a complete depression of the key-lever.
29. In a typewriting machine having type-bars and key-levers to actuate the type-bars, a normally inoperative coupler for each key-lever, a power-driven permanently magnetized actuator common to all the couplers, a cam for each coupler operative to shift the coupler into the magnetic field of said actuator for a key-lever-driving connection with the actuator by a manual initial depression of its key-lever, camming means having non-
- magnetic properties carried by each coupler which, in entering the magnetic field of said actuator, operates to cam said coupler out of the magnetic field of the actuator and to release the coupler and key-lever from the power-driven actuator at the end of a complete depression of the key-lever, and means carried by each key-lever operative to adjust the coupler relatively to the key-lever to predetermine the operative depression of the key-lever in typing.
30. In a typewriting machine having type-bars and depressible key-levers to actuate said type-bars, a power-driven permanently magnetized actuator, and normally inoperative couplers carried by the key-levers and movable thereby into the magnetic field of the actuator upon the initial depression of said key-levers, each coupler having a magnetizable section to magnetically clutch the actuator to complete the depression of its key-lever and a non-magnetic face to bear against the actuator and effect the release of the coupler from the magnetic attraction of said actuator and release the fully depressed key-lever.
31. In a typewriting machine having type-bars and key-levers operative to actuate said type-bars, a power-driven permanently magnetized continuously rotating actuator universally operative to fully depress any initially depressed key-lever to actuate its type-bar, and a normally inoperative coupler between each key-lever and the rotating magnetized actuator, said couplers automatically effecting a magnetic clutching engagement with said actuator by the manual initial depression of their key-levers, each coupler separating itself from said actuator by its own movement in fully depressing a key-lever.
32. In a typewriting machine, the combination with a typing mechanism, of a motor-driven continuously rotating and permanently magnetized cylinder, and means operatively connected to and movable by one member of the typing mechanism, adapted, upon entering the magnetic field of the cylinder, to become effective as a cylinder-driven element to actuate the whole typing mechanism to type a character.
33. In a typewriting machine, the combination with a typing mechanism, of a motor-driven continuously rotating and permanently magnetized cylinder, and means operatively connected to and movable by one member of the typing mechanism and which means, upon entering the magnetic field of the cylinder, becomes effective as a cylinder-driven element to actuate the whole typing mechanism to type a character and then to automatically remove itself from the magnetic control of the cylinder to release the driven member of the typing mechanism.
34. In a typewriting machine, the combination with a typing mechanism, of a motor-

driven continuously rotating and permanently magnetized cylinder, and means operatively connected to and movable by one member of the typing mechanism and which means, upon entering the magnetic field of the cylinder, becomes effective as a cylinder-driven element to actuate the whole typing mechanism to type a character, and then to automatically remove itself from the magnetic control of the cylinder prior to the typing moment to release the typing element to its momentum for a typing impact.

35. In a typewriting machine having type-bars and depressible key-levers to actuate said type-bars, an actuating armature connected to each key-lever, a cylinder disposed transversely of and adjacent the series of armatures, and an electric motor to continuously drive the cylinder, said cylinder enclosing a coil electrically excited when a circuit is closed through the motor to rotate the cylinder, said coil when excited conducting magnetism of the cylinder that becomes operative during the initial depression of a key-lever to first clutch the armature by magnetic attraction and then carry the armature by friction to complete the depression of the semi-depressed key-lever to actuate its type-bar.

36. In a typewriting machine having type-bars and depressible key-levers to actuate said type-bars, an actuating armature connected to each key-lever, a cylinder disposed transversely of and adjacent the series of armatures, and an electric motor to continuously drive the cylinder, said cylinder enclosing a series of coils that form a continuous unit electrically excited when a circuit is closed through the motor to rotate the cylinder, said coils when excited conducting magnetism of the cylinder that becomes operative during the initial depression of a key-lever to first clutch the armature by magnetic attraction and then carry the armature by friction to complete the depression of the semi-depressed key-lever to actuate its type-bar.

37. In a typewriting machine having type-bars and depressible key-levers to actuate said type-bars, an actuating armature connected to each key-lever, a cylinder disposed transversely of and adjacent the series of armatures, and an electric motor to continuously drive the cylinder, said cylinder enclosing a plurality of coils wound for opposite polarities and assembled within the cylinder to form a continuous unit of alternating polarity and electrically excited when a circuit is closed through the motor to rotate the cylinder, said coils when excited conducting magnetism of the cylinder that becomes operative during the initial depression of a key-lever to first clutch the armature by magnetic attraction and then carry the armature by friction to complete the depression of the semi-depressed key-lever to actuate its type-bar.

38. In a typewriting machine having type-bars and depressible key-levers to actuate said type-bars, an actuating armature connected to each key-lever, a cylinder disposed transversely of and adjacent the series of armatures, and an electric motor to continuously drive the cylinder, said cylinder enclosing a coil and having commutator-rings at each end thereof connected to the terminals of the enclosed coil and brushes in contact with the rings which are wired to the motor-circuit to electrically excite the coil when the motor-circuit is closed, said coil when excited conducting magnetism of the cylinder that becomes operative during the initial depression of a key-lever to first clutch the armature by magnetic attraction and then carry the armature by friction to complete the depression of the semi-depressed key-lever to actuate its type-bar.

39. In a typewriting machine having type-bars and depressible key-levers to actuate said type-bars, an actuating armature connected to each key-lever, an actuating cylinder for the armatures disposed transversely of and adjacent the series of armatures, and an electric motor to continuously drive the cylinder, said cylinder enclosing a coil electrically excited to magnetize the cylinder when a circuit is closed through the motor to rotate the cylinder, said cylinder also having means for adjusting the plane thereof to determine a universal position for coaction with the armatures.

40. In a typewriting machine having type-bars and depressible key-levers to actuate the type-bars, an actuating armature pivotally pendent from each key-lever and spring pressed to normal inoperative position, a power-driven permanently magnetized cylinder co-operative with all the armatures, and individual tripping cams operative to vibrate an armature into the rotating magnetic field of the cylinder when said armature is partially depressed by its key-lever, to thereby effect a full depression of the key-lever to actuate its type-bar.

41. In a typewriting machine having type-bars and manually-depressible key-levers to actuate the type-bars to type, power-driven magnetic means to actuate the key-levers at will to type, including an actuating armature connected to each key-lever, and a power-driven permanently magnetized cylinder common to all the armatures, said armatures being shifted into the magnetic control of the rotating cylinder by a partial depression of the key-levers.

42. In a typewriting machine, the combination with a type-bar having a manually depressible key-lever to actuate the type-bar, of a motor-rotated magnetized mechanism for driving the key-lever, means operated by the key-lever to connect the key-lever with the magnetized driven mechanism to actuate

the type-bar, a stop to positively arrest the power-driven depression of the key-lever in advance of the typing position, and means intermediate the key-lever and the type-bar operative to free the type-bar from the control of the key-lever at the position of its greatest velocity, enabling the type-bar to type and recoil by its acquired momentum.

43. In a typewriting machine having type-bars, the combination of power-driven means including a continuously rotating universal friction clutch-member to actuate the type-bars, an individual friction clutch-member operatively connected to each type-bar, keys to predetermine the clutching engagement for each individual clutch-member with the universal clutch-member, means to maintain the clutching engagement, and means carried by each individual clutch-member operative to disengage the clutch, said last-mentioned means including a wedge-member rendered operative by the throw of the individual clutch-member to be interposed between said individual member and the universal clutch-member.

44. In a typewriting machine having type-bars, the combination of power-driven means including a continuously rotating electromagnetized universal friction clutch-member to actuate the type-bars, an individual clutching armature-member operatively connected to each type-bar to be thrown by said universal member, keys to effect the clutching engagement of the armature-members with the universal clutch-member, and means operative to disengage each armature-member at the end of its throw.

45. In a typewriting machine having type-bars, the combination of power-driven means including a continuously rotating electromagnetized universal friction clutch-member to actuate the type-bars, an individual clutching armature-member operatively connected to each type-bar to be thrown by said universal member, keys to effect the clutching engagement of the armature-members with the universal clutch-member, and non-magnetic means carried by each armature-clutch-member and operative to sever the magnetic grip of said clutch by the throw of the armature.

46. In a typewriting machine having type-bars, the combination of power-driven means including a continuously rotating electromagnetized universal friction clutch-member to actuate the type-bars, an individual clutching armature-member operatively connected to each type-bar to be thrown by said universal member, keys to effect the clutching engagement of the armature-members with the universal clutch-member, and non-magnetic camming means carried by each armature-clutch-member and operative to sever both the magnetic and the mechanical

grip of the universal clutch-member by the throw of the armature.

47. In a typewriting machine, the combination with a typing mechanism, of a motor-driven continuously-rotating and permanently-magnetized cylinder, an intermediary operatively connected to and movable with one member of the typing mechanism, and operable upon entering the magnetic field of the cylinder to become effective as a cylinder-driven element to actuate the whole typing mechanism to type a character, and means for adjustably connecting said intermediary to its typing member to time the entrance of said intermediary into the magnetic clutching field of the cylinder.

48. In a device of the character described, the combination with key-levers, of a power-driven rotary magnetic actuator for all of the key-levers as each lever is depressed, and an adjusting means for the actuator to change the relative position of the actuator to the key-levers to control the extent of the actuation of the key-levers by the actuator.

49. In a device of the character described, the combination with key-levers, of a power-driven rotary magnetic actuator, armature-coupling-members connectible by the key-levers with the actuator to drive the key-levers, means to disconnect the coupling members from the actuator to release the key-levers, and an adjustable mounting for each coupling-member connecting them to the key-levers, to thereby control the timing of the disconnecting means.

50. In a device of the character described, a motor-driven rotatable magnetic actuator representing a cylindrical member and composed of a series of cylindrical magnet sections assembled to provide peripheral flux gaps, a magnetizing coil to induce magnetism of opposite polarity enclosed within the successive magnet sections, and ring commutators connecting the terminals of the assembled magnetizing coils with a main circuit.

51. In a device of the character described, a motor-driven rotatable magnetic actuator, composed of a series of cylindrical magnet sections enclosing a series of coils, mounted on a shaft, with peripheral flux gaps between adjoining magnet sections, said coils being interconnected and wound to induce magnetism of opposite polarity in adjacent magnet sections, and ring commutators mounted on the shaft and connecting to the terminals of the assembled coils with a main circuit.

52. In a typewriting machine having a series of type-actions, a rotary type-action-operating cylinder having a plurality of built-up sections, each section having a coil, the coils having similar poles adjacent each other and effective to establish a magnetic field of substantially uniform density throughout the length of the cylinder.

53. In a typewriting machine, the combina-

tion of a motor-driven magnet forming a universal clutch-member, a series of type-actions, individual armatures forming clutch-members and connected to the type-actions to drive them, and means for selectively bringing said armatures under the influence of the magnetism of the universal clutch-member, to enable the latter to drive any type-action.

54. In a typewriting machine, the combination of a motor-driven magnet forming a universal clutch-member, a series of type-actions, individual armatures forming clutch-members and connected to the type-actions to drive them, means for selectively bringing said armatures under the influence of the magnetism of the universal clutch-member, to enable the latter to drive any type-action, and means for effecting the release of each armature after driving the type, to enable the type to print by momentum, the magnetic clutch-member and the individual armatures each being adjustable, one relative to the other, to establish a uniform position where each type is released.

55. In a typewriting machine, the combination of a printing mechanism, a power-driven member for operating the same, including a friction-coupler pivoted to one part of the printing mechanism and arranged to be thrown by an electro-mechanical friction engagement with said power-driven member, a key-lever operable when depressed to swing said coupler into the frictional control of said power-driven member, said power-driven member having magnetic characteristics that reinforce the frictional grip of the coupler independently of the key-pressure for a typing interval, and means carried with the thrown coupler and operative to engage the power-driven member at the end of the typing interval, to cam said coupler free of the power-member.
